Des. 16609

Elonir J. Key, of Lowell, Mass.
Assignor to
The Lowell Manufacturing Company
Letters Patent No. 669 - Dated Nov. 11th 1862.

The schedule referred to in these Letters Patent and making part of the same to all whom it may concern:

Be it known that I, Elonir J. Key, of Lowell, in the County of Middlesex and State of Massachusetts, have originated and designed a new Pattern for carpets or other fabrics, of which the following is a full, clear and exact description, reference being had to the accompanying drawings, making part of this specification.

A. in the centre, is a figure composed of scrolls and small balls, resting on the mottled ground. B.

In corner 1. is one fourth of a rosette resting on the veined figure 2. which is surrounded by the ground. D.

The figures of corner 4. are similar to those of corner 1.

In corner 5. is one fourth of an eight pointed outline figure surrounded by the ground 6.

The scalloped and star shaped figures of corner,

Dec 1669

7 are surrounded by the ground, 8.

The mottled ground B. is enclosed by the frame. 9.

The colors employed for the different portions of the design may be varied to suit the taste and wish of the manufacturer.

Claim

What I claim as my invention and desire to secure by letters patent, is the design or pattern for carpets, or other fabrics, herein set forth.
